DESIGN FOR A COMBINATION SEMITRAILER TANK AND PACKAGE DELIVERY BODY

Ferdinand C. Buchanan and Edward H. Gill,
Kansas City, Mo., assignors to Andrew A.
Kramer, Kansas City, Mo.

Application March 2, 1936, Serial No. 61,446

Term of patent 14 years

To all whom it may concern:

Be it known that we, Ferdinand C. Buchanan and Edward H. Gill, citizens of the United States, residing at Kansas City, in the county of Jackson and State of Missouri, have invented a new, original, and ornamental Design for Combination Semitrailer Tank and Package Delivery Body, of which the following is a specification, reference being had to the accompanying drawing forming a part thereof.

In the drawing:

Fig. 1 is a side elevation of our new design.

Fig. 2 is a rear elevation thereof.

Fig. 3 is a top plan view thereof, and Fig. 4 is an enlarged vertical sectional view through the upper portion of our new design, taken substantially on the line 4—4 of Fig. 1.

We claim:

The ornamental design for a combination semitrailer tank and package delivery body substantially as shown.

In testimony whereof we hereunto subscribe our names this 22nd day of February, 1936.

FERDINAND C. BUCHANAN.
EDWARD H. GILL.
